TELEVISION RECEIVING APPARATUS

Georg Schubert, Berlin, Germany, assignor to the
firm Fernsh Aktien-Gesellschaft, Zehlendorf,
near Berlin, Germany

Application April 20, 1932, Serial No. 606,471
In Germany April 24, 1931

4 Claims. (Cl. 178—6)

In television practice the sources of light usually employed for giving a luminous surface are the known surface glow discharge lamps. The ordinary surface glow discharge lamp has the 5 advantage that it can be controlled with simple means and without particular expenditure, but in the case of high image point numbers it provides relatively faint television pictures.

It has in fact already been proposed to employ the positive column of gas discharges, but heretofore, in order to be free from disturbances, they have been operated with modulated high frequency, exceedingly high voltages being required for this purpose. Moreover it has not 10 been possible to eliminate these disadvantages even by employing oxide cathodes. Heretofore, for the operation of luminous tubes it has always been necessary to employ a high-frequency transmitting valve with low frequency modulation.

In contradistinction to the previous complicated methods of operating with high frequency, the present invention consists in operating the luminous tube with continuous voltage and in 15 connecting it directly in series with the output valve of the low-frequency amplifier, so that the anode current of the output valve, for example an R E 604, flows through the luminous tube. In contradistinction to any other method of 20 coupling, such as chokes, transformers, etc., this circuit connection has the additional advantage of working perfectly independently of the frequency. It is immaterial whether the luminous tube is provided with a heated cathode or not, 25 and likewise, the cathode may be heated by direct current or alternating current.

Certain difficulties arise, however, in operating the positive-column luminous tube with continuous voltage. The luminous tube is readily 30 extinguished at the moment modulation begins, and with modulation of varying strength it works so irregularly as to be unsuitable for satisfactory reproduction. As mentioned hereinbefore this unreliable working has also resulted 35 in the fact that heretofore luminous tubes were never operated with continuous voltage but always with high-frequency, because the difficulties do not then occur.

According to a feature of the present invention, all the aforementioned difficulties in the 40 operation of luminous tubes with continuous voltage may be obviated by exciting the luminous tube with high frequency. Very small outputs are sufficient for this, and quite ordinary 45 broadcasting valves, for example an R E 134 or

weaker valves, will suffice. The coupling of the high frequency is preferably effected capacitatively and, since very small capacities are sufficient for coupling, this may be done by simply placing behind the luminous tubes a metal plate 5 to which is connected a lead from the high-frequency circuit. The other lead is preferably connected directly to the cathode. At the same time, the metal plate used for capacity coupling may also be constructed in the form of a metallic mirror, in which case it will increase the uniformity of the luminosity of the image surface.

The accompanying drawing shows the complete circuit of a luminous tube for television 15 purposes, the said tube being, according to the invention, operated with continuous voltage and excited with high frequency. In the drawing, the output valve of the low frequency amplifier is shown at 1, 2 is the luminous tube connected 20 in series therewith, 3 is the oscillating valve for generating the high frequency and 4 is the metal plate or metallic mirror which is used for the capacity coupling of the luminous tube to the high-frequency circuit. A resistance 5 bridged 25 by a capacity 6 is used for regulating the current intensity of the luminous tube. All the remaining details will be gathered without difficulty from the circuit diagram itself.

Having now particularly described and ascertained the nature of my said invention and in what manner the same is to be performed, I declare that what I claim is:—

1. In a television system, the combination of a low-frequency amplifier having an output valve, 35 a variable resistance and a positive-column luminous tube having a descending current voltage characteristics and having its electrodes spaced longitudinally of the tube connected in series with said resistance in the anode circuit 40 of said output valve, a condenser is shunt to said resistance, and means for continuously capacitatively exciting said luminous tube with high frequency.

2. The combination in a television system, of a 45 low frequency amplifier having an output valve, a positive-column luminous tube and means for continuously capacitatively exciting said luminous tube with high frequency, means for connecting said positive-column luminous tube in 50 the anode circuit of said output tube including a variable resistance arranged in a lead connecting one electrode of said luminous tube with the anode of said output tube, and a condenser shunted across said resistance.

3. The combination in a television system, of
a low frequency amplifier having an output
valve, a positive-column luminous tube and
means for continuously capacitatively exciting
said luminous tube with high frequency, means
5 for connecting said positive-column luminous
tube in the anode circuit of said output tube
including a variable resistance arranged in a
lead connecting one electrode of said luminous
10 tube with the anode of said output tube, and a
condenser in shunt to said resistance, said means
for capacitatively exciting said luminous tube
with high frequency including a high frequency
circuit, an oscillating valve for generating high
15 frequency in said high frequency circuit, and a
metallic plate connected with said last named
circuit and arranged behind said luminous tube
for establishing a capacitative coupling between
said high frequency circuit and said luminous
20 tube.
4. The combination in a television system, of

a low frequency amplifier having an output
valve, a positive-column luminous tube and
means for continuously capacitatively exciting
said luminous tube with high frequency, means
5 for connecting said positive-column luminous
tube in the anode circuit of said output tube in-
cluding a variable resistance arranged in a lead
connecting one electrode of said luminous tube
with the anode of said output tube, and a con-
denser in shunt to said resistance, said means for 10
continuously capacitatively exciting said lu-
minous tube with high frequency comprising an
independent high frequency circuit, an oscillat-
ing valve for generating high frequency in said
high frequency circuit, and a metallic plate hav-
ing a reflecting surface connected with said last 15
named circuit and arranged behind said lu-
minous tube for establishing a capacitative cou-
pling between said high frequency circuit and
said luminous tube. 20
